UNITED STATES PATENT OFFICE.

GEORGE T. EUARD, OF BRADFORD, ILLINOIS.

VALVE-SPRING LIFTER.

1,345,153.

Specification of Letters Patent. Patented June 29, 1920.

Application filed September 4, 1919. Serial No. 321,593.

To all whom it may concern:

Be it known that I, GEORGE T. EUARD, a citizen of the United States, and a resident of Bradford, in the county of Stark and State of Illinois, have invented a new and Improved Valve-Spring Lifter, of which the following is a full, clear, and exact description.

This invention relates to improvements in valve spring lifters, an object of the invention being to provide a device of the character stated, which is especially adapted for use in connection with the valves of internal combustion engines, such as employed on automobiles in general use, but may of course be adapted for various other valves.

A further object is to provide improved means for lifting the pressure disk on the valve stem against the action of the valve spring and maintain the disk at approximate right angles to the stem so as not to exert any angular or torsional strain on the parts.

Heretofore, various forms of valve spring lifters have been employed, but due to the pivotal connection of the lever or movable member, the pressure disk is caused to assume an angular position in accordance with the angular position of the lever. With my improved device this objectionable feature is entirely overcome.

A further object is to provide a device of the character stated, which will hold the pressure disk in any position of adjustment and yet allow a quick release, as occasion may require.

With these and other objects in view the invention consists in certain novel features of construction, and combinations and arrangements of parts, as will be more fully hereinafter described and pointed out in the claims.

In the accompanying drawings—

Figure 1 is a view in elevation illustrating my improvements; and

Fig. 2 is a top plan view of the device detached.

1 represents an engine cylinder, 2 a valve stem, 3 a pressure disk on the valve stem and 4 a coiled spring around the stem exerting downward pressure on the disk. This is common valve construction and forms no part of the present invention.

My improved valve spring lifter has a bar 5 which is made with a longitudinal slot

6 in its upper portion and at its lower end has an opening 7 receiving an eye 8 of a hook 9, the said hook adapted to engage over a fixed bar of the engine cylinder 1.

A normally horizontal lifting arm 10 is 60 provided with a forked end 11 adapted to straddle the rod 2 and engage the under face of the disk 3. This lifting arm 10 is connected by a link 14 with the shorter end of an operating lever 12. The lever 12 is pivotally supported on the bar 5 by means of a rivet 13, and rivets 15 and 16 respectively connect the ends of the link 14 with the arm 10 and lever 12.

A diagonal link 17 is pivotally connected 70 at one end by means of the rivets 16 and at its other end is connected by a rivet 18 which extends through the arm 10 and is movable in the slot 6 of bar 5. The arm 10 has a laterally projecting finger 19 which is adapted to be pressed downwardly to release the arm from its holding position, as will more fully hereinafter appear.

When the device is in the position indicated in Fig. 1 and the longer end of lever 80 12 is forced downwardly, by reason of the links 14 and 17, the arm 10 will be elevated and maintained in a normally horizontal position. By reason of the frictional engagement of the rivets with the several parts and 85 the diagonal strain imparted by the link 17, the arm 10 will hold the disk 3 in any position to which it is adjusted so that it is not necessary to maintain a pressure on the lever 12 for this purpose. When, however, it is, 90 desired to release the disk, a slight pressure on the finger 19 will overcome the binding action of the parts and the disk can be permitted to lower.

Various slight changes may be made in 95 the general form and arrangement of parts described without departing from the invention, and hence I do not limit myself to the precise details set forth but consider myself at liberty to make such changes and alterations as fairly fall within the spirit and scope of the appended claims.

I claim:

1. A valve spring lifter, comprising a bar, a lifting arm, a lever pivotally connected to 105 the bar, a link connecting the arm and the lever, and a second link connected to the lever and to the arm and movably connected to the bar.

2. A valve spring lifter, comprising a bar, 110

a lifting arm movably connected to the bar, a lever pivotally connected to the bar, a link connecting the lever and the arm, and a diagonally positioned link connected at one 5 end to the pivotal connection of the lever and the first-mentioned link, and at its other end connected to the arm at its point of movable connection with the bar.

3. A valve spring lifter, comprising a bar, 10 a lifting arm, a lever pivotally connected to the bar, a link connecting the arm and the lever, and a second link connected to the lever and to the arm and movably connected to the bar, said arm having a forked end 15 and a laterally projecting finger on the other end of said arm.

4. A valve spring lifter, comprising a bar, a lifting arm movably connected to the bar, a lever pivotally connected to the bar, a link 20 connecting the lever and the arm, and a

diagonally positioned link connected at one end to the pivotal connection of the lever and the first-mentioned link, and at its other end connected to the arm at its point of movable connection with the bar, said arm 25 having a forked end and a laterally projecting finger on the other end of said arm.

5. A valve spring lifter, comprising a bar having a longitudinal slot therein, a hook on the lower end of the bar adapted to engage a fixed support, an arm normally at right angles to the bar, a lever pivotally connected to the bar, a normally vertical link connecting the arm and the lever, a diagonal link connected at one end to the pivotal connection between the first-mentioned link and the lever, and a securing device connecting the other end of said diagonal link with the arm and movable in the slot of the bar. 30 35

GEORGE T. EUARD.
